UNITED STATES PATENT OFFICE.

JOHN F. FINAN, OF CUMBERLAND, MARYLAND.

ROLL-PAPER HOLDER AND CUTTER.

No. 846,194.

Specification of Letters Patent.

Patented March 5, 1907.

Application filed October 9, 1906. Serial No. 338,102.

To all whom it may concern:

Be it known that I, JOHN F. FINAN, a citizen of the United States, residing at Cumberland, in the county of Allegany and State of Maryland, have invented a new and useful Improvement in Roll-Paper Holders and Cutters, of which the following is a specification.

My invention relates to a roll-paper holder and cutter for the use of merchants and others for facilitating the tearing off of sheets of paper of any desired size from a roll for wrapping up packages.

It relates to that form of roll-paper holder having a stand with a vertical spindle on which the roll of paper is held, and it is designed to apply to this form of roll-paper holder a feature heretofore employed in horizontal roll-paper holders for facilitating the seizure of the edge of the paper between the thumb and forefinger preparatory to pulling it out and tearing off the sheet.

A yielding cutter-bar composed of two flat plates with a space between them for the paper to pass through has heretofore been applied to roll-paper holders having a horizontal axis, and my present invention is designed to provide a construction of upright roll-paper holder in which this general principle may be made available.

To this end it consists in an upright deflectable cutter-bar combined with the roll-holder and in other features of improvement, as hereinafter described with reference to the drawings, in which—

Figure 1 is a perspective view; Fig. 2, a plan view. Fig. 3 is a vertical section; Fig. 4, a sectional detail, and Fig. 5 is a detail of the bearing-ring for the turn-table.

In the drawings, A represents a base adapted to sit upon the counter and having a rigid stationary vertical spindle B.

C is a turn-table which turns about the spindle, which latter passes through the center of the roll of paper P as supported on the turn-table. The turn-table C is made to rotate easily and cheaply by two annular face-plates c c', one fixed to the top of the base A and the other fixed to the bottom of the turn-table concentrically to the spindle and having between them a loose ring c'', made of a single piece of metal, as seen in Figs. 3 and 5, also surrounding the spindle and forming the bearing-surface for the turn-table and its load.

The base-plate A is extended at one side at

A', and on this extension is erected the upright deflectable cutter-bar D D. This cutter-bar consists of two similar parallel bars, which are connected at top and bottom, but have a narrow space between them, with the edges d d next to the roll flared to form a converging throat, and with the outer edges d' d' sharpened to form a cutting edge for the paper.

Near the upper end of the cutter-bar the two edges next to the paper-roll are cut transversely and turned around to form bearing-surfaces d² d² for the thumb and forefinger to permit the upper end of the cutter-bar to be thrust inwardly or tilted on its lower end toward the paper-roll. The bottom end of each cutter-bar is flanged and connected to a plate a, hinged on one side at a' to the base, and the outer portion of the flanged end is provided with headed bolts a² a², whose lower heads are contained within the base or below a plate a³, attached to the base, and have spiral springs a⁴ around them, which when the top of the cutter-bar is tilted toward the roll, as in Fig. 1, allow the upright cutter-bar to yield on its hinge a' and then cause it to be restored to its vertical position as soon as the pressure of the hand is withdrawn. This deflectable cutter-bar thus has a radial swing- 85

ing movement to an oblique position in relation to the edge of the paper, its lower end being always at a fixed distance from the axis of the roll, while its upper end is movable to and from the roll with a varying angle 90

in relation to the axis of the roll.

After a sheet of paper has been torn off along the edge of the cutter-bar, the edge of the paper will be concealed between the cutter-bars; but when the hand is applied to the finger-rest or bearing-surfaces d² and the top of the cutter-bar is tilted inwardly to the roll the upper edge of the paper protrudes between the two members of the cutter-bar and into the hollow of the same hand and between the thumb and forefinger of the same hand which deflects the bar, so that the paper edge may in one movement be exposed, received into the hand, and grasped thereby to be pulled out. When so seized, the paper is pulled out, the deflectable cutter-bar resumes its true vertical position, and a sweep of the hand holding the paper edge causes the sheet to be quickly, conveniently, and accurately torn off at any desired line, according to the size of the sheet wanted.

I have shown springs a⁴ for retracting the

cutter-bar; but it will be perceived that the weight of the cutter-bar is on one side of its tilting axis and gravity alone may suffice for restoring the bar, especially if its base be extended and weighted. I may also use spring-hinges or any other form of springs for restoring the bar.

When the upper end of the cutter-bar is thrust toward the paper-roll, it is important that the paper should pass between the two sections of the cutter-bar instead of merely buckling or opening around the roll. To prevent this buckling or opening of the paper, a weighted metal ball E has an eye e hung upon an inclined arm F, which causes the ball always to gravitate against the outer layer of paper at the top of the roll and hold it against opening or buckling from the inward movement of the cutter-bar. The inclined arm F is connected to a cap G, which has a socket that fits on top of the spindle B. This cap has a conical boss or hub g, on which is fitted the central opening of a tube or cone of cord x. This cap is locked rigidly to the top of the spindle by a forked slot b in the top of the spindle into which there drops the inner end of the arm F, which is extended to the center for this purpose.

Near the upper end of the spindle, but inside the roll, is a stop-spring b², constructed like an umbrella stop-spring. This spring is forced inward when slipping the roll of paper on the spindle, for which purpose the cap is first removed and then when the lower core-spool s passes this spring the latter springs out and passes beneath the upper core-spool s, so that this cannot descend accidentally into the roll, and thus distort the roll and interfere with its correct action in unwinding.

To prevent the end of the cord from becoming caught with the paper as it enters the tapering throat of the cutter, I provide a means for holding the free end of the cord up and out of the way of the cutter. For this purpose a cross-head H is suspended from the ceiling in horizontal position by means of eyes h h and hooks in the ceiling, and two eyes h' h' are secured to the bottom of the cross-head on opposite sides of a handle-rod I, which at the top is fixed to the cross-head at right angles thereto and which at its lower end is bent into a loop to form a handle. On the rod I slides a traveling ring J. The end of the cord from the spool on the roll-holder is then threaded through the eyes, as shown, and also through the traveling ring J. When the free end of the cord is pulled, the ring J rises on rod I, and when a sufficient quantity of the cord is broken off the ring J gravitates toward the bottom and in doing so draws up the free terminal end of the cord, as shown.

In mounting the roll of paper it may be placed on the spindle to run either to the left or right, and in either case the paper will be

cut in the same manner, the only change required being to turn the cap-piece half-way round, so that the ball will be on the other side of the roll. With regard to the function and value of the ring c² this requires no recess or raceway in either of the face-plates, but is retained in position by surrounding the spindle B, so that it cannot get out of place. The frictional resistance which it affords is so slight that it allows tender paper to be pulled off without wild tearing, and yet it does not allow momentum to accumulate in the roll when pulling the paper off, as does a sensitive ball-bearing, but furnishes a frictional resistance that causes the roll to stop when the pull on the paper ceases, thus avoiding the unwinding of a surplus amount of paper from momentum and the incidental crumpling of the same.

I claim—

1. A paper-roll holder and cutter, comprising means to rotarily sustain the roll and a radially-swinging cutter-bar having a throat through which the paper passes one end of said cutter-bar being pivoted a fixed distance from the axis of the roll and the other end being movable to and from the axis of the roll at varying angles thereto.

2. A paper-roll holder and cutter, comprising means for holding a paper-roll about an upright axis and an upright deflectable cutter-bar having a throat through which the edge of the paper passes, said cutter being hung to swing radially about its lower end to or from said axis at varying angles thereto.

3. A paper-roll holder and cutter, comprising means for holding a paper-roll about an upright axis and an upright deflectable cutter-bar having a throat through which the edge of the paper passes, a hinged connection for the lower end of the cutter-bar and one or more springs for holding the cutter-bar in normal upright position.

4. A paper-roll holder and cutter, comprising means for holding a paper-roll about an upright axis and an upright deflectable cutter-bar having a hinge on one side of its lower end and headed bolts and springs on the other side.

5. A paper-roll holder and cutter comprising a base having a central fixed upright spindle with a metallic face-plate on top of the base and closely surrounding the spindle, a turn-table arranged about the spindle and having on its lower side a metal face-plate closely surrounding the spindle, a detached but integral ring arranged around the spindle between the two face-plates and loosely turning between the face-plates, and means for tearing off the paper from the roll.

6. A paper-roll holder and cutter, comprising means for rotarily holding the roll in upright position about a vertical axis, an upright and yielding cutter-bar and a gravitating and swinging weight hung upon a support

from the center of the roll-holder and bearing against the upper edge of the paper-roll.

7. A paper-roll holder and cutter, comprising a spindle for the roll having a slotted top end, a cap with a socket fitting the top end of the spindle and having an arm extending across the socket and fitting in the slot of the spindle and having its outer end bent up-

wardly, a gravitating and swinging weight hung upon said inclined arm and a yielding cutter-bar.
